UNITED STATES PATENT OFFICE

133,817

DESIGN FOR A TEXTILE FABRIC

Henry W. Sandground, Larchmont, N. Y.

Application August 5, 1942, Serial No. 107,824

Term of patent 3½ years

To all whom it may concern:

Be it known that I, Henry W. Sandground, a citizen of the United States, residing at Larchmont, Westchester county and State of New York, have invented a new, original, and ornamental Design for a Textile Fabric, of which the following is a specification, reference being had to the accompanying drawing, forming part thereof, wherein the figure is a plan view of a textile fabric, showing my new design, the complete unit of the design being enclosed by dot and dash lines.

I claim:

The ornamental design for a textile fabric, substantially as shown and described.

HENRY W. SANDGROUND.
